UNITED STATES PATENT OFFICE.

JOSEPHINE McNULTY SPENCER, OF FLORENCE, NEBRASKA.

DOLL.

1,307,218.

Specification of Letters Patent. Patented June 17, 1919.

Application filed March 23, 1917. Serial No. 156,851.

To all whom it may concern:

Be it known that I, JOSEPHINE McNULTY SPENCER, a citizen of the United States, residing at Florence, in the county of Douglas 5 and State of Nebraska, have invented a new and useful Doll, of which the following is a specification.

My invention relates to dolls, and the object is to provide a sanitary doll. This I obtain by using a detachable covering upon 10 which the features or characteristics of the doll are embroidered or otherwise marked, and which cover can be easily removed and washed or otherwise cleansed.

In the accompanying drawing, Figure 1 is 15 an elevation of a doll embodying my improvements. Fig. 2 is a rear view showing one manner of securing the detachable covering, and Fig. 3 a similar view showing a 20 slightly different fastening means. Fig. 4 is a view of the doll body.

At 1 I have indicated the body of a doll 25 which comprises a torso, head, arms and legs, such body being formed after the manner which is common in making "rag" dolls.

Completely enveloping the body 1 and conforming to the torso, head, arms, and legs, thereof is a covering 2, a placket 3 permitting its ready application to the body. The placket is closed either by a button and button-hole fastening 4, as shown in Fig. 2, or by tapes 5, as shown in Fig. 3. On the front of the cover at that portion which corresponds to the head of the body markings in simulation of a human face are provided, being 30 embroidered or otherwise indicated. 35

The covering 2 is preferably made of stockinet, outing flannel, bear skin cloth or other suitable material, especially of elastic fabrics, or it may be crocheted or knitted of 40 yarns, cord or threads.

I claim as my invention:

In a doll, a body portion having a head, arms and legs, and a removable unitary cover for completely enveloping and conforming 45 to the shape of said head, arms and legs, said cover being provided with markings in simulation of a human face, and equipped with a fastening means.

JOSEPHINE McNULTY SPENCER.
